UNIVERSALLY ADJUSTABLE INDEX FOR
WORKHOLDERS

Alonzo K. Elliott and Theodore T. Munn, Indianapolis, Ind.

Application September 8, 1947, Serial No. 772,694

7 Claims. (Cl. 51—234)

1

This invention relates to a universally adjustable work holder for the precision formation of tools, etc., having predetermined regular and irregular shapes.

This application is a continuation-in-part of application Serial No. 658,980, filed April 2, 1946, and entitled Universally adjustable work holding means, now Patent No. 2,476,361, dated July 19, 1949, as will be apparent from a comparison of Fig. 1 of the respective applications.

The chief object of the present invention is to improve the invention disclosed and claimed in said patent for it has been found that after approximately two years' daily use that the control bar and its mounting collect diamond dust which causes relative wear therebetween sufficient to introduce a minor error so the structure is no longer absolutely correct within the limits of its original construction.

A corollary objective hereof is to extend the range of usefulness of the control bar.

An object secondary thereto is to combine the stop and lock features of said application disclosure and to extend the length of life of such composite structure.

A further object of the present invention is to extend the range of operation of the first application structure by an extensible and universally adjustable mount for the micrometer thereof.

Other objects and features of the present invention will be set forth more fully hereinafter.

The full nature of the invention will be understood from the accompanying drawings and the following description and claims:

In the drawings, Fig. 1 is a perspective view of the preferred embodiment of the invention.

Fig. 2 is a rear elevation of the upper portion thereof and on a larger scale.

Fig. 3 is a perspective view of the micrometer, its mount and associated end of the supporting control bar and same is taken oppositely with respect to Fig. 1 and the parts being disposed at 90° to the position shown in Fig. 1.

Fig. 4 is a central sectional view through the control bar and mount for same.

In Fig. 1 of the drawings herein 10 indicates a base portion from which at one end projects upwardly the arm portion 11 and the forward extension 12. The rear face and bottom face of portions 10 and 11 are disposed transversely of each other for transverse mounting as desired or required.

Portions 11 and 12 terminate in a barrel or collar portion 13 which mounts the control bar

14 as hereinafter pointed out. Rotatably mounted in portion 13 between the bar and barrel is a sleeve portion 15 which on its forward end is enlarged as indicated at 16. Its periphery adjacent the forward end of portion 13 includes scale 17. Vernier devices at the quadrant points as indicated at 18 and 19 are also provided.

Extending forwardly and at 45° or so to the sleeve is arm 20 which terminates in a forward extension 21 that is suitably socketed at 22 to pivotally support portion 23, same being supported at 24 upon an axis transverse to and intersecting the sleeve axis.

Portion 23 is rigid with body 25 that terminates in a apertured tongue 26. A work support 27 is adjustably carried by a base 28 having apertured ears 29 taking tongue 26 therebetween. A clamp 30 secures same together. A clamp 31 secures 23 and 24 together.

20 The aforesaid briefly describes such portions as are identical or similar to parts disclosed in said application. The work holder can be adjusted to and fro upon member 28. The latter may be tiltably adjusted upon the axis of clamp 30.

25 Member 25 may be tiltably adjusted upon a transverse axis coincident with the axis of clamp 31 and that, as stated, is transverse to and intersects with the axis of the sleeve 15. Work carried by support 27 can thus be accurately disposed from time to time as desired or required.

30 The forward end of bar 14, see Figs. 1 and 3, is flattened as at 33. A collar 35 mounts clamp screws 36 whereby the collar is clamped to the bar end. The collar includes neck 37 tapped as at 38. An arm 39 includes hole 40 and counterbore 41 to accommodate shank 42 and head 43 of a screw, the threaded end of which is threaded into neck 37 at 38.

35 The arm 39 is disposed parallel to axis of bar 14 although the arm, by loosening the clamp screw, can be swung about the axis thereof and clamped in the desired position. Whenever desired or required a spacer sleeve 44 of gauge block type may be interposed between the neck and arm. This sleeve may be one half, an inch, an inch and a half or two inches in length. Of course, an appropriate length clamp screw would be utilized with each sleeve.

40 The outer end of the arm terminates in a socket 45 and same and arm 39 adjacent thereto is slotted at 46. A clamp unit 47 serves to contract the socket upon the relatively stationary portion 48 of a micrometer 49 having contact element 50.

45 Reference will now be had to Figs. 1, 2 and 4.

The bar 14 includes four quadrant disposed slots 51 so that it can be locked in any of the four positions. This bar has its slots disposed from about the center to the rear end.

Sleeve 15 in which bar 14 is rotatably and slidably mounted in the bore 52 thereof has at the forward end 52a a pivoted closure plate 53 so that when the bar is removed this hole is closed and dirt cannot enter same.

During work formation also, since the bar 14 completely occupies bore 52, no diamond dust or grit can enter said bore forward end, thus eliminating a source of wear incident to use. Since the grooves or slots 51 extend to the rear end of the bar 14, same can be disposed forwardly to a maximum amount.

As shown in Fig. 4, sleeve 15 is rotatably supported in bushing 54. The sleeve is rotatable therein by means of worm wheel portion 55 meshing with worm 56 actuatable by crank 57. The sleeve can be clamped as at 58, when desired.

Herein the portion 13 at its upper portion and near the rear end includes a way slot or groove 59. A U-shaped member 60 is suitably secured to portion 13 by screw 61 which also extends into bushing 54.

The confronting sides 62 of the U-shaped member have a slight taper (1°). A wedge member 63 frictionally seats therein. The rear end thereof extends beyond member 60 and includes a depending tongue 64, the lower end of which seats in a groove 51 to hold bar 14 in predetermined angular position.

Threaded on the rear and projecting end of sleeve 15 at 65 is control ring 66 having T-slot 67 therein. Adjustably secured therein are stops 68 and 69. Herein, the exterior of U-shaped member 60 is tapered as at 70 so that stops 68 and 69 may have line contact therewith. These stops are provided for repetitious measuring or work rotation upon the axis of the sleeve bore incident to crank operation when multiple cuts or passes are required and incident to blending of radii.

Wear of the stop occurs equally upon both faces of member 63 and both faces 62 so that bar centering will be maintained for many years of use. In other words, wear, as it occurs is automatically taken up. In the present instance member 60 serves as stops for stop members 68 and 69 and a self-centering seat for lock or stop 63-64.

The structure disclosed herein operates substantially as disclosed in Patent No. 2,476,361 supra except as hereinbefore noted. Herein bar 14 includes arcuately spaced slots 51 with which locator 64 is selectively seatable when the bar is sufficiently projected. When locator 64 is seated in a slot near the end remote from the bar end the slots terminate within the sleeve. Slots 51 bear a predetermined angular relation to micrometer base 35 locating flat portion 33 on said bar.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, as defined in the appended claims.

The invention claimed is:

1. Work holding structure comprising a tubular base, a sleeve having a bore therethrough and rotatable in the base tubularity and a plurality of successively hinged members, hinge means connecting one of the members to the sleeve, the hinge axis of successive members being disposed in transverse relation, the sleeve rotational axis and the hinge axis of the hinge means intersecting, a control bar adapted for micrometer support and rotatably and slidably supported in the bore of a sleeve, the micrometer support portion at one end, of the bar having a plurality of elongated parallel slots therein at least near the other end and terminating at that end, and a slot receivable locator carried by the base and selectively receivable by any parallel slot and anywhere along the length thereof.

2. A structure as defined by claim 1 wherein there is provided means for reversely rotating said sleeve, adjustable spaced stops carried at the rear end of said sleeve and disposed oppositely with respect to said bar, and a locator support upon the base and selectively engageable by the stops for limiting reverse rotation of the sleeve by the reversely rotating means.

3. A structure as defined by claim 2 wherein the locator support comprises a channel member having sloping sides, the slope being towards each other and the rotational axis of the sleeve, the locator having a body portion with complementary sides seating in the channel member and terminating in a tongue selectively seatable in a bar groove.

4. A micrometer support structure for a work holding device substantially as described comprising a longitudinally slidable and step by step rotatable control bar, means for slidably and rotatively supporting the bar, a lock for determining the stepped position of the bar, an auxiliary base carried by one end of the bar, and a neck on the base and disposed transverse to the axis of the bar, an arm disposed in offset relation to that axis, a pivotal connection between one end of the arm and the neck, a clamp securing the arm and neck together in adjusted angular relationship, and a clamp type micrometer anchorage at the other end of said arm.

5. Structure as defined by claim 4 wherein there is provided between the arm and the neck a guage type spacer extension.

6. Structure as defined by claim 1 wherein the length of the bar slots is such that when the locator is seated in the rear end of a slot the other ends of the slots terminate within the sleeve.

7. Structure as defined by claim 6 wherein a cover plate is hingedly supported on the forward end of the sleeve immediately adjacent the base seated portion thereof for closing the sleeve bore at that end.
